STUD ASSEMBLY FOR LUGGAGE

Morris Leonard Duskin, Chicago, Ill.

Application December 8, 1947, Serial No. 790,415

7 Claims. (Cl. 190—26)

1

This invention relates to protective covers for luggage. Specifically, this invention deals with studs adapted to be secured to the bottom panel of a flexible fabric luggage cover for supporting the weight of the enclosed luggage during shipping of the same.

The supporting stud of this invention is particularly adapted to be attached to the bottom panel of a luggage cover, one stud being disposed at each corner thereof. As is well known in the luggage field, luggage covers are made of a durable, relatively inexpensive cloth, such as canvas, and are used to enclose expensive luggage for protecting it from the rough usage normally given luggage during shipping.

To prevent excessive wear and abrasion of the bottom of the cover itself, small pedestals or foot members, usually taking the form of inverted, segmental spherical headed studs, are secured at the four corners of the bottom panel of the cover with the headed portion disposed to rest on the ground and the shank end of the stud fastened in the canvas bottom. Thus, the bottom panel of the cover is held spaced from the ground.

It is understood, of course, that the enclosed piece of luggage also has supporting stud members. If these latter studs align themselves directly above the studs of the cover, the weight of the piece of luggage will be transmitted directly through the aligned studs to the ground. However, if the luggage studs are not directly above the cover studs, the weight of the luggage must be transmitted from the luggage studs through the canvas bottom panel to the cover studs. Heretofore, this transmission of the weight of the luggage through the canvas of the cover has caused tearing of the canvas around the upper end of the cover studs and has resulted in the premature failure of the luggage cover as a whole.

According to the features of the present invention, the corners of the bottom panel of the luggage cover may be provided with outer reinforcement strips of leather or imitation leather, affording a double bottom panel at these critical corner areas. The upper end of each stud penetrates the outer reinforcement panel or wall and is secured in a heavy felt washer between the two panels, as by separating and bending over the split upper end of the stud. The bent over ends are embedded in the felt washer and thus, a soft, yieldable felt surface is presented to the canvas cover when it is pressed downwardly by the weight of the piece of luggage.

It is accordingly an object of this invention to

2

provide means for preventing the tearing of the fabric of a luggage cover when a piece of luggage is supported therein.

Another object of this invention is to provide a novel stud and stud washer designed and arranged to support the weight of a piece of luggage without presenting sharp edges to the fabric of the cover.

A further object of this invention is to provide a novel stud washer which completely surrounds the upper end of the stud and which is sufficiently rigid to transmit the weight of the luggage to the load bearing head of the stud and is sufficiently yieldable to prevent tearing of the 15 canvas of the cover where it contacts the washer.

On the drawings:

Figure 1 is a side elevational view of a luggage cover according to the teachings of this invention, with the handle portion of an enclosed piece 20 of luggage shown in dotted lines;

Figure 2 is an end elevation of the luggage cover of Figure 1;

Figure 3 is a fragmentary side elevational view, partly in section and partly broken away, of the 25 luggage cover of Figure 1; and

Figure 4 is a fragmentary enlarged vertical sectional view taken through the center of the novel stud and washer assembly of the present invention.

As shown on the drawings:

In Figure 1, the reference numeral 10 indicates a luggage cover constructed according to the teachings of this invention. This cover is preferably made of a heavy grade of canvas having its two sides, top and bottom made from a single piece of material 12. At either end, a pair of end members, 13 and one not shown, and 14 and 14a, respectively, are sewed onto the member 12, thus providing two half cover assemblies joined at the bottom by the bottom portion 40 of the member 12.

A fastener 15, such as a zipper, is disposed at the lower corner at either end of the cover, and is arranged to move toward the central portion 45 of the upper panel to close the cover by drawing the marginal edges of each half cover together. The space between the ends of the closed fastener 15 defines an opening 16 through which a handle 16b of an enclosed piece of luggage 11 may project for convenience in carrying the covered luggage. The portion of the canvas cover immediately around this opening 16 may be reinforced, if desired, by strips of leather 16a sewed on either side thereof.

As illustrated in Figures 1 and 2, at each end

of the bottom of the cover a U-shaped reinforcing strip 17 is sewed onto the member 12 and secured in the seam joining the end panels to the member 12. These strips 17, which may be made of a durable, pliable material, such as leather or imitation leather, form, together with the member 12, a double panel at the ends of the cover.

According to the teachings of this invention, a metal washer 19 (Figure 4) and a superimposed felt washer 20 are adapted to be positioned at each corner of the bottom panel of the cover between the leather strips 17 and the canvas member 12, having their central openings aligned with an aperture 11a in the leather strip 17. A stud 22 having a segmental spherical head 22a seated in a semi-spherical support member 23 extends through the aperture 11a, the metal washer 19 and the felt washer 20 and has its outer split end portion 22b separated and pressed down into the felt washer 20, as shown in Figure 4. The felt washer 20 thus forms a cushioning collar, having an annular portion 20a that extends around and above the split end of the stud to contact the canvas member 12. With this construction, it is readily seen that any load on the felt washer 20 will be transmitted through the metal washer, the leather strip 17 and the semi-spherical support member 23 to the head 22a of the stud. As long as the annular portion 20a extends above the separated ends of the stud, this portion of the stud will not contact the canvas of the member 12.

The stud and washer assembly may most conveniently be secured on the leather strip 17 before the strips are sewed onto the cover.

In Figure 3, the piece of luggage 11 is shown as enclosed in the cover 10 and as having foot portions in the form of segmental spherical headed studs 11a secured at the corners of the bottom of the piece of luggage. It is seen that the weight of the piece of luggage causes the stud 11a to bend the canvas member 12 over the edge of the felt washer 20. This washer presents a rounded, yieldable edge to the canvas of the member 12, which edge will not tear or cut into the canvas.

It is also within the scope of this invention to make the height of the felt washer 20 substantially equal to the height of the foot 11a of the enclosed piece of luggage so that the weight of the luggage will be wholly or partially transmitted directly from the luggage to the annular ring 20a of the felt washer. This would eliminate, to a large extent, the load which has heretofore caused tearing of the canvas cover.

It is also a part of this invention to make the washer 20 of any semi-rigid yieldable material having properties similar to that of felt.

From the foregoing discussion, it is seen that there is provided in this invention a novel stud and washer combination which effectively prevents tearing of the fabric of a luggage cover. This novel stud and washer is relatively inexpensive and very easy to install.

It will be understood that details of construction may be varied without going beyond the scope of the appended claims.

I claim as my invention:

1. A supporting stud assembly for a luggage cover or the like comprising an inverted stud having a shank portion and a segmental spherical head portion, means to space said head portion below the bottom wall of the cover, said shank portion having a split outer end projecting

through the wall, and a semi-rigid washer disposed about the shank portion of the stud above the wall of the cover to receive the bent over end portions of said stud when said stud is secured onto the wall, said washer affording a cushioning ring around and above the bent over end portions of the stud.

2. In combination in a luggage cover, a bottom wall, a reinforcing strip secured to each corner area of said bottom wall, a plurality of supporting stud assemblies secured to said strips at the corners of said bottom wall, each of said assemblies comprising a stud having a split end shank portion and a head portion, means to space said head portion below said reinforcing strip, and a semi-rigid washer disposed about the shank portion of the stud above said reinforcing strip and projecting above the split end of said stud to present a smooth, yieldable surface to said bottom wall.

3. In a luggage cover having reinforcing strips secured to the corners of the bottom wall thereof, a supporting stud assembly secured at each corner of the bottom wall, each supporting stud assembly comprising a stud having a head and a straight shank, said shank being disposed in an aperture in the reinforcing strip and being split at its outer end, a spacer member abutting the lower surface of the reinforcing strip and having an aperture therethrough and a seat for receiving the head of the stud, a rigid washer disposed about the shank of said stud and on the upper surface of the reinforcing strip, a semi-rigid washer disposed on said rigid washer and about the shank of said stud, said semi-rigid washer providing an annular ring around and above the stud when the ends of the stud are separated and bent downwardly into said washer.

4. In a luggage cover having a reinforcing strip secured to each of the corners of the bottom wall thereof, a supporting stud assembly secured at each corner of the bottom wall of the cover and comprising a stud having a head and a split shank portion, said split shank portion extending through the reinforcing strip, a spacer washer disposed between the head of the stud and the reinforcing strip and having a shoulder for receiving the head of the stud, and a semi-rigid washer disposed about the split shank of the stud, providing a ring around and above the end of the stud when the ends are separated and bent downwardly into said washer, the weight of luggage enclosed in said cover being transmitted through said semi-rigid washer and said spacer washer to the head of said stud.

5. In combination with a flexible cover for a piece of luggage which has foot members secured to the bottom panel thereof, a bottom wall for said cover, a reinforcing strip secured to each corner area of said bottom wall, a plurality of supporting stud assemblies secured to said strips at the corners of said bottom wall, each of said assemblies comprising a stud having a head portion spaced below said reinforcing strip by support means, a split shank portion projecting therefrom and through said strip, and a washer disposed about the shank of the stud and above said reinforcing strip and projecting above the split end of said stud, said washer being of a thickness substantially equal to the height of the foot members of the enclosed piece of luggage whereby the weight of the luggage will be transmitted directly to said washers.

6. In a luggage cover having reinforcing strips secured to the corners of the bottom wall there-

of, a supporting stud assembly secured at each corner of the bottom wall, each supporting stud assembly comprising a stud having a head and a straight shank, said shank being disposed in an aperture in the reinforcing strip and being split at its outer end, and a semi-rigid washer disposed about the shank of said stud, said semi-rigid washer providing an annular ring around and above the stud when the ends of the stud are separated and bent downwardly into said washer. 10

7. A protective covering for articles such as luggage having a bottom wall provided with a plurality of support members, said support members comprising a yieldable supporting element positioned on an interior surface of said bottom wall so as to support the article in spaced relation to said interior surface, an outer supporting element positioned on an exterior surface of said bottom wall and located directly below said yieldable element on the interior surface, and a metallic fastening means passing through both said inner and said outer supporting elements and

5 clamping them to the opposite sides of said bottom wall, the upper surface of the inner most element extending upwardly beyond the innermost end of said metallic fastening means.

MORRIS LEONARD DUSKIN.
